G. G. WILEY

FRictional SWING SASH LOCKING FIXTURE

Filed August 15, 1924

UNITED STATES PATENT OFFICE.

GEORGE G. WILEY, OF CHICAGO, ILLINOIS, ASSIGNEE TO STREETER-AMET WEIGHING & RECORDING COMPANY, OF CHICAGO, ILLINOIS, A CORPORATION OF ILLINOIS.

FRICTIONAL SWING-SASH LOCKING FIXTURE.

Application filed August 15, 1924. Serial No. 732,162.

To all whom it may concern:

Be it known that I, GEORGE G. WILEY, a citizen of the United States, residing at Chicago, in the county of Cook and State 5 of Illinois, have invented certain new and useful Improvements in Frictional Swing-Sash Locking Fixtures, of which the following is a specification.

This invention has for its object to provide 10 a fixture for swing-sash windows and for doors which will permit the sash or door to be swung to any desired position and will frictionally retain it in such position against the action of air currents tending to swing 15 the same to other positions.

A further object of the invention is to provide 20 a fixture, adapted to function as aforesaid, which is simple, light, easily mounted on the sashes or doors and their frames, and which occupies minimum space besides being 25 of neat appearance.

A further object of the invention is to provide 30 a frictional fixture of the type specified wherein the frictional resistance to complete closure of the window from an open position, is overcome to the extent necessary to prevent the window from springing back to a slightly open position following closure thereof.

35 A suitable embodiment of the invention is illustrated in the accompanying drawings, wherein:—

Fig. 1 is a perspective view of a fixture, constructed in accordance with the invention, mounted on window frame and window sash, the latter being shown in open position.

Fig. 2 is a top plan view of the mounted fixture, a part of the window-casing being shown in section.

40 Fig. 3 is a sectional view on the line 3—3 of Fig. 2.

The said fixture comprises a pair of opposed circular disks A and B, having slightly dished opposed middle portions and which are equipped with integral radial arms C and D, respectively, said disks having central openings for the passage of the pivot element E for pivotally associating the same. The pivot element E includes a threaded shank portion F to receive the nut G for adjusting the pressure exerted by the spring H upon the disks A and B for resisting free relative rotation of the latter. The spring H includes the central or hub portion provided with an opening for the passage of the

50 pivot element E, and a plurality of radial ogee curved arms 1 bearing at their end portions upon one of said disks. A washer J is preferably interposed between the nut G and said spring.

The arm C of the disk A is of considerably greater length than the arm D of the disk B, both said arms being pivotally secured at their outer ends to one flange of each of two L-shaped brackets K and L, respectively, the bracket K for the arm C being secured to the window or door-frame M and the bracket L for the arm D being secured to, preferably, the top rail of the sash or door N. The said arms are offset slightly from the plane of the 60 contacting surfaces of the disks so as to permit them to overlap each other when the sash is in closed position, without coming into surface contact with each other.

When the window or door is closed, the 65 bracket L will be disposed between the bracket K and the disks A and B, the stems C and D being then disposed at a very acute angle to each other, the whole fixture being then disposed in close proximity to a face of the 70 sash or door and also closely adjacent to the top of the window-casing for protection against the weather by the latter, the fixture being most generally applied to inwardly 75 swinging windows and doors and, therefore, 80 disposed outwardly of the sash or door.

It will be obvious that as the sash is moved from open to closed position, the pivotal movement of the longer arm with respect to its bracket will be far in excess of that of the 85 shorter arm, whereas, as the sash approaches closed position the pivotal movement of the shorter arm with respect to its bracket will gradually exceed that of the 90 longer arm and through the final substantially five degrees of closing movement of the sash the longer arm will remain substantially inert. The frictional resistance to 95 relative pivotal movement of the disks is, of course, constant and tends to spring the 100 longer arm to an extent which causes the sash to spring back slightly from closed position. A stop O is, therefore, provided on the bracket K in the path of the arm C to limit its pivotal movement and thus permit the sash to be moved and retained in final 105 closed position. The said stop O also serves to effectually determine the relative positions of the brackets K and L on the window frame and sash in installing the device as, 110

by throwing the arm C into contact with the stop, the person installing the fixture need only apply the same to the window when the sash is fully closed in order to determine the points at which the fastening screws must enter the casing and sash.

Obviously, while it is most convenient to provide the stop O on the bracket K, the same may be otherwise applied to perform its first mentioned function.

I claim as my invention:—

A swing-sash fixture comprising two circular disks having oppositely dished central portions and central openings, a pivot bolt passing through said openings, a plural-armed flat spring having a central opening for the passage of the threaded shank of said bolt and bearing at the ends of its arms upon the peripheral portion of one of said disks,

a nut on said bolt for adjusting the pressure exerted by said spring and retaining the same in position a radial arm integral with and extending from the circumferential edge of each of said disks and slightly offset from the plane of the contacting faces of said disks to permit said arms to overlap without coming into contact with each other, one of said arms being about twice the length of the other thereof, a bracket adapted to be mounted on a window casing, and a bracket adapted to be mounted on a sash, the longer arm pivotally connected with the first named bracket and the shorter arm with the other bracket, the latter adapted to be mounted on the sash to occupy a position between the disks and the bracket mounted on the casing.

GEORGE G. WILEY.
